UNITED STATES PATENT OFFICE.

GUSTAF B. BIRCH AND JAMES A. CAMERON, OF BROOKLYN, NEW YORK.

POCKET COIN-HOLDER.

No. 904,244.

Specification of Letters Patent. Patented Nov. 17, 1908.

Application filed April 3, 1908. Serial No. 424,714.

To all whom it may concern:

Be it known that we, GUSTAF B. BIRCH and JAMES A. CAMERON, citizens of the United States, and residents of Brooklyn, in the county of Kings and State of New York, have invented certain new and useful Improvements in Pocket Coin-Holders, of which the following is a specification.

The invention relates to improvements in pocket coin-holders; and it consists in the novel features and structure hereinafter described, and particularly pointed out in the claims.

The object of the invention is to provide a small, neat, inexpensive, compact coin-holder adapted to be conveniently carried in the pocket and to hold a series of coins of the same denomination in such manner that the coins may one after another be removed from the holder with entire ease.

The holder of our invention is especially useful and convenient for holding a series of five-cent pieces or nickels to be used as car-fare on cars on which the passengers are required to promptly pay their fare at the entrance door and expected to produce the exact amount of fare. In these cars the conductor is stationed on the rear platform and does not pass through the car to collect the fares. In utilizing these "pay as you enter" cars it is exceedingly necessary that passengers pay their fare promptly and produce the exact amount thereof, and it is highly desirable that the passengers be enabled to readily produce the fares and deliver the same with one hand, leaving the other hand free to sustain themselves against accident in the event of the sudden starting or stopping of the car. It is also a great convenience to the passenger to be enabled to readily find his car-fare without pulling out a handful of change and searching through it for a nickel. The holder of our invention is also useful for other occasions, as, for illustration, in enabling the user to conveniently carry a series of five-cent pieces for use on prepayment "slot" telephone instruments.

The holder of our invention, in its preferred form, is constructed of two elongated plates each flanged at its side edges to em-

brace and lap over the side edges of the coins to be slid upon the same between its flanged edges, said plates each having integral springs cut therefrom in position to become 55 flexed against the coins when the latter are introduced to the holder for firmly though detachably holding the coins, and said plates being secured back to back so that the holder thus constructed may receive coins on 60 each side thereof, said coins lying flat and in line with one another on each side of the holder. The holder thus constructed will conveniently hold an adequate number of coins without being bulky or occupying undue space in any ordinary pocket, and said holder may be conveniently "loaded" with the coins and will permit the ready removal of the same therefrom by an outwardly exerted pressure on them of the thumb of the 70 same hand holding the device, this pressure causing the coins, one after another, to slide outwardly from the holder.

The invention will be fully understood from the detailed description hereinafter presented, reference being had to the accompanying drawings, in which:

Figure 1 is a top view of a coin-holder constructed in accordance with and embodying our invention, the coins being absent 80 from the obverse side of the holder and two coins being indicated, by dotted lines, as present in the reverse side thereof; Fig. 2 is a view of the holder reversed to illustrate the two coins held thereby; Fig. 3 is a longitudinal section through the holder on the dotted line 3-3 of Fig. 2, coins being illustrated within both sides of the holder; Fig. 4 is a vertical transverse section through the holder on the dotted line 4-4 of Fig. 1, 90 coins being illustrated within both sides of the holder; Fig. 5 is an enlarged section corresponding with Fig. 4 of a portion of the holder and is presented to illustrate more clearly the details of the construction; Fig. 95 6 is a longitudinal horizontal section through a modified construction of the holder, in which the springs in lieu of being in the main body of the plates are formed in the flanges at the side edges thereof, the section 100 being on the dotted line 6-6 of Fig. 7; Fig. 7 is an edge view of the same, and Fig. 8 is

a top view of a further modified form of the invention, the construction shown in Fig. 8 being of greater capacity than that presented in Figs. 1 to 4 inclusive.

- 5 In the drawing, referring to Figs. 1 to 5 inclusive, 10 designates the holder as consisting of two elongated plates 11, 12 secured together, back to back, by eyelets 13 punched in one plate and extended through and riveted in holes formed in the other plate. The plates 11, 12 may be secured together by solder or in various well-known mechanical ways but we prefer to connect them by portions struck from one plate and entering holes in the other plate, since this forms a very convenient and durable means of connection and allows the plates to come close together.

Each plate 11, 12, is rounded at its ends and at each side edge is formed with right-angled flanges comprising members 15, 16, the members 15 denoting the depth of the holders and the members 16 extending inwardly toward each other to lap upon opposite edges of the coins 14 held between the members 15. The edge flanges on the plates 11, 12, receive, guide and hold the coins upon the plates, while exposing nearly the entire outer side of the coins.

30 Each plate 11, 12 has cut from its body portion a spring-tongue 18 for each coin to be placed in the holder, this tongue 18 being projected outwardly to exert its pressure against the coin for firmly binding the same at its edges against the flange members 16. Each plate of the holder shown in Figs. 1 to 5 inclusive is intended to hold two coins and hence each of said plates is equipped with two spring tongues 18, one for each coin. The plates 11, 12 are flanged before they are secured together, and hence when they are united back to back their flanges extend outwardly in opposite directions, as shown in Figs. 4 and 5, whereby the holder becomes not only compact but adapted to receive coins 14 at both of its sides.

The coins 14 are slipped edgewise below the flanges 16 of the plates 11, 12 and upon the spring-tongues 18, which exert their force to bind the coins against said flanges and firmly but detachably hold them in position. Each plate 11, 12 is separately adapted to hold coins and when of the length illustrated in Figs. 1, 2 and 3 will hold two coins. Each plate may be lengthened to hold more than two coins but for the sake of convenience to the user we prefer to secure two short plates 11, 12 back to back so that the holder may receive coins at both of its sides and thus be rendered small and compact and at the same time of sufficient capacity to hold enough coins for purposes

of car-fare, telephone messages and the like. The coins may be readily applied to the holder and removed therefrom. It is entirely convenient to push the coins from the holder by pressing outwardly against the same with the thumb of the hand containing the holder, the other hand being thus left free to hold packages or grasp the rail or other part of a car platform. One coin may be pushed from each end of each side of the holder or both coins at each side of the holder may be pushed from one end thereof, as may be deemed most convenient by the user. The flange-members 16 pass inwardly over the coins to only a limited extent and hence almost the entire outer surfaces of the coins are exposed to be engaged by the thumb of the hand containing the holder.

We prefer the construction of holder shown in Figs. 1 to 5 inclusive, but illustrate in Figs. 6 and 7 a holder comprising two flanged plates 19, 20 secured together back to back and corresponding with the flanged plates 11, 12 of Figs. 1 to 5 with the one exception that in lieu of the spring-tongues 18 to engage the inner faces of the coins, the construction shown in Figs. 6 and 7 employs spring-tongues 21 cut from the edge flanges thereof to engage the opposite edges of the coins and hold the latter in position on the plates.

In Fig. 8 we show a holder of greater capacity than that illustrated in Fig. 1, the holder of Fig. 8 being enabled to hold four coins on each side thereof, each plate being formed with four right-angular flanges affording the two pairs of members 22, 23 between which the coins may be placed, as shown. The holder of Fig. 8 corresponds in construction with that shown in Fig. 1 with the exception that in lieu of continuing the edge flanges along the edges of the plates, the flanges in Fig. 8 are given a right-angular outline so that the holder may receive coins at both its sides and ends instead of only at its ends. While the holder shown in Fig. 8 possesses greater capacity than that illustrated in Fig. 1 it is also more bulky.

What we claim as our invention and desire to secure by Letters Patent, is:

1. A pocket coin-holder comprising two elongated plates having rounded ends and secured together back to back, said plates each having edge flanges to receive the edges of the coins and spring-tongues to engage the individual coins, said holder being thus adapted at each side to receive a series of coins placed flat and in line with each other; substantially as set forth.

2. A coin-holder comprising two elongated flat plates of substantially the width of the

coins and secured together back to back, said plates each having right angular edge flanges to confine and lap over upon the edges of the coins, whereby a series of coins lying flat and edge to edge may be held on each plate with their outer faces almost entirely exposed, said plates having spring means for detachably retaining the coins thereon.

Signed at New York city, in the county ¹⁰ of New York and State of New York, this 1st day of April A. D. 1908.
